J. B. BUCKLEY

BOILER

Filed March 10, 1926

Inventor.
John B. Buckley;
By R. S. Berry,
Attorney.

UNITED STATES PATENT OFFICE.

JOHN B. BUCKLEY, OF LOS ANGELES, CALIFORNIA.

BOILER.

Application filed March 10, 1926. Serial No. 93,580.

The present invention relates to improvements in boilers for apparatus for steam cleaning automobile chassis and the principal object resides in the provision of means for circulating the feed water through the boiler in such manner as to continuously subject the same to the heat radiations from a source of heat supply disposed at the base of the boiler and successively recirculating the preheated water through the boiler for subjection to the heating radiations.

Another object of the invention contemplates the provision of expansive connections between the heating coil and supporting column and the heating coil and drum to allow for the quick detachment of the coil in its entirety from the boiler.

A further object of the invention is to provide in a boiler of the character described, novel connecting means for the coil fittings to the water column and steam drum and for hermetically sealing the said connections.

In the drawings:

Fig. 1 is a vertical section of the improved boiler with a portion of the drum in elevation and illustrating the novel connections between the coil and the column and drum;

Fig. 2 is an enlarged vertical section of the connection between the coil and drum taken on line 2—2 of Fig. 1;

Fig. 3 is a similar view of the connection between the coil and the column;

Fig. 4 is a cross section of the drum on line 4—4 of Fig. 1.

Referring specifically to the drawings in which similar reference characters designate similar parts in each of the several views, my invention in its present embodiment comprises substantially a cylindrical boiler comprising an outer jacket 10 and an inner casing 11 spaced inwardly therefrom and suitably connected together by rivets or the like.

The space between the jacket 10 and inner casing 11 is packed with a suitable heat insulating medium such as mineral or asbestos wool 12 and mounted on the upper end of the casing 10 and secured thereto in any appropriate manner is a water drum 13, provided with a plurality of vertically extending radially disposed flue tubes 14, as illustrated in Fig. 4.

The drum 13 is provided with a base plate 15 and a top closure plate 16, which are respectively formed with downwardly direct-

ed annular flanges 17 and 18 and rivets 19 and 20 pass through suitable openings in the flanges and upper and lower marginal edges of the drum casing 13 for rigidly connecting the said base and top plates 15 and 16 to the drum casing.

Base plate 15 is formed with a relatively large central opening 21 and the metal at this point is outwardly flared to form an annular flange 22, which is threaded to receive the upper end of tubular column 23, which latter extends through the central part of the inner casing 11 to a point slightly above the lower end thereof.

Likewise, the base plate 15 is provided with a plurality of radially disposed openings 70 adapted for the reception of the lower ends of the flue tubes 14, whereby the latter are in communication with the inner casing 11, the upper ends of the flue tubes pass through suitable openings in the top closure plate 16 75 and provide a suitable means for escaping gases.

The lower end of the column 23 is exteriorly threaded as at 24, and engages within the vertically disposed threaded opening of 80 a three-way fitting or T-fitting 25, which likewise, is provided in its arms with aligning horizontal openings interiorly threaded as at 26 and 27.

A peripherally threaded plug 28 is adapted for engagement with the threads 27 of one of the horizontal fitting openings and is formed centrally with an opening adapted for the reception of the threaded end 29 of a pipe 30, leading from the feed water supply.

The opposite horizontal opening of the fitting 25 is adapted for the reception of a plug 31, formed with a head portion 32, which is exteriorly threaded as at 33 to engage the threads 26 of the last mentioned horizontal opening of the fitting.

Plug 31 is likewise formed with an inwardly directed extension 34, exteriorly threaded as at 35, and is formed with smooth 100 central bore, through which extends the pipe 36, having elbow connection 37, with a stub pipe 38, attached by an elbow connection 39 to the lower convolution of a water heating coil 40, of double helico-volute configuration. 105

The upper and lower coil sections are united by interconnecting elbow fittings 41 and 42, and the uppermost convolution 43 of

the upper coil section has elbow connection 44 with a pipe 45, which latter extends through a smooth bored opening in the base plate 15 of the drum 13.

5 The connecting means for the pipes 36 and 45 to the column 23 and drum 13 to allow for the quick detachment of the coil 40, is as follows:—

10 The inner end of the pipe 36, has slip connection with the plug 31 and is exteriorly threaded at its inner end as at 46, for the reception of a lock nut 47 which bears against the confronting flat surface of a collar 48, having a reduced exteriorly threaded extension 49 formed thereon. A sleeve 50 is formed with an interiorly threaded opening 51, adapted for the reception of the threaded extension 35 of the plug 31, and its enlarged end 52, is interiorly threaded as at 53 and 15 adapted for the reception of the threaded extension 49 of the collar 48. A beveled seat 54 is provided interiorly of the collar 48 and a gland 55 is interposed between the seat 54 and the inner end of the extension 49 of the 20 collar 48. The pipe 36 extends through the central openings of the gland 55, collar 48 and lock nut 47, and the collar 48 when tightened in the sleeve 50, urges the inner extension 49 of the collar 48 against the gland 55, serving to force the same outwardly upon the seat 54, and the pipe 36 is thus rendered leakproof at its connection with the above recited elements within the three-way fitting 25. The 25 lock nut 47 serves to hold the collar 48 against loosening.

30 The pipe 45 connecting the upper section of coil 40 and the water drum 13 extends through an annular sleeve 56, having a ring 57 encircling the lower end thereof and by means 35 of which, it is spot welded to the base plate 15 of the water drum. Pipe 45 is exteriorly threaded as at 58 and is spaced from the interior wall of sleeve 56 and a packing 59 of suitable heat insulating material, is interposed between the pipe and sleeve as clearly 40 illustrated in Fig. 2.

45 A washer 60 is positioned between the packing 59 and the threaded extension 61 of a collar 62, which latter is adapted to be screwed within the interiorly threaded upper end of the sleeve 56 and having its lower end engaging washer 60.

50 Collar 62 is formed with a flat annular head 63, by means of which it may be screwed inwardly for connection with the sleeve 56, and when so adjusted it contacts with washer 60 and compresses the gland 59 to provide a waterproof and steamproof joint for the connections and pipe 45. A lock nut 64 is 55 mounted on the threaded end 58 of pipe 45 and when adjusted engages the flat outer surface of the collar head 63, whereby the said collar and pipe are held in position in the sleeve 56.

60 65 A burner, preferably gas, not illustrated,

may be secured in any desirable manner to the base of the boiler proper and the heat emanating therefrom circulates upwardly through the inner casing 11, being in contact with the coil, column and connections as described.

70 An opening 65 is formed in the lower part of the boiler casing contiguous to the fitting connections 37 and 38 between the pipe 36 and the lower coil convolution and an opening is likewise provided in the water drum 13 75 contiguous to the base plate 15, however, the drum opening is sealed by a closure device comprising cup plates 66 and 67, the peripheral edges of which are held in close relation to the inner and outer walls respectively of the opening by means of a bolt 68 on the outer end of which is threaded a wing nut 69 adapted to be tightened upon the bolt 68 to engage plate 67 to effect a water and steam tight joint.

80 The heat from the burner passes upwardly 85 through the inner boiler casing 11, contacting with the three-way coupling 25 and coil 40, and a constant supply of water and steam passes through pipe 30 into the three-way coupling 25 and the coil through pipe 36, and 90 fittings 37 and 38 and accumulates in the steam drum 13, through the fitting connections 44 and 45.

95 The heat in the upper part of the boiler casing 11 passes upwardly through the flue pipes 14, serving to maintain the temperature of the steam in the drum 13 and a take-off pipe 100 70 leads from the drum and functions to distribute the steam to any desired point or points.

105 The water in the drum is further adapted for recirculation through the boiler and may pass downwardly through the column 23 to the interior of the three-way coupling 25 from whence it is passed again through pipe 36 to the coil 40 and to the drum again.

110 In this manner, the water is constantly circulated through the boiler and maintained at an even temperature.

115 Heretofore, in heaters of this type, the replacement of the heating coils has not been possible and by provision of the slip connections for the pipe 36 and 45, the openings in the boiler casing and drum, it is possible to quickly detach the coil from the connections 120 which is accomplished in the following manner:

125 The water supply pipe 30 is unscrewed from the plug 28 and pulled through the openings in the casing walls 12 and 13 and then 120 plug 28 provided with openings 71 in its outer surface, is gripped with a spanner wrench and unscrewed from the three-way coupling 25. The lock nut 47 is then unscrewed from the threaded end of pipe 36, so that the same 125 may be slipped through plug 31 and collar 48, effecting its release from the three-way coupling 25. The water drum 13 having been drained, the closure plates 66 and 67 are uncoupled from the drum wall and access is had 130

to the upper lock nut 64, which latter is unscrewed from the threaded end of pipe 45, having slip connection with the collar 62.

In this manner, the coil in its entirety may 5 be removed by swinging the same towards the casing opening 65 to effect the release of the pipe 36, from its connections with the three-way fitting 25.

It is possible of course, to unscrew the plug 10 31 and collar 48 after the locking washer 47 has been removed, and the same applies to the drum connection, wherein the collar 63 may be unscrewed from the sleeve 56.

It is obvious that I have provided an apparatus of the character described wherein maximum circulation of the feed water is effected and wherein the coil is capable of quick detachment from the boiler for repair or replacement.

20 Although I have herein illustrated and described only one form of heater embodying my invention, it is to be understood that various changes and modifications may be made therein without departing from the spirit 25 of the invention and the spirit and scope of the appended claims.

What I claim is:—

1. A boiler casing, a heating coil therein, a central tubular column, there being a steam 30 chamber with which the upper end of said column and coil communicate, an inverted T-fitting the stem of which is secured to the lower end of said column, the arms of said fitting being directed toward diametrically 35 opposite sides of the boiler, a supply pipe leading to one of said arms through the boiler wall at that side, a feed pipe for said coil having a detachable section connected with the opposite arm of said T-fitting, means 40 within the last mentioned T-fitting arm to detachably fasten said feed pipe therein, said

means being accessible and operable by means of a suitable tool inserted through the opposite arm of the T-fitting, an internally and externally threaded plug in said last named 45 arm, said supply pipe being screwed into said plug and being adapted for unscrewing therefrom and withdrawal through the boiler wall to permit the removal of said means and subsequent releasing of said coil feed pipe 50 by the insertion of a suitable tool through the arm of said T-fitting which receives said plug.

2. The combination, with a boiler casing having therein a steam drum; of a T-fitting, a column one end of which communicates with 55 said drum and the other with the stem of said T-fitting, a heating coil, a feed pipe therefor which communicates with one arm of said T-fitting by means of a slip joint, a water-tight fitting around said joint, a supply pipe, a removable plug in the other arm of said T-fitting through which said supply pipe communicates therewith and a retaining nut on the end of said feed pipe for the coil, said nut being accessible for unscrewing by a suitable tool inserted through the opposite arm of the T-fitting after said plug and supply 60 pipe have been removed therefrom.

3. The combination with a boiler having a steam drum; of a T-fitting, a column communicating between said drum and the stem of 70 said T-fitting, a heating coil, a feed pipe therefor communicating with one arm of said T-fitting by means of a slip joint, and a packing gland arranged interiorly of said T-fitting 75 affording a water tight connection around said joint, said packing gland being accessible through the other arm of said T-fitting.

In testimony whereof I have affixed my 80 signature.

JOHN B. BUCKLEY.
